UNITED STATES PATENT OFFICE.

GEORGE B. MADDOCKS, OF ALLSTON, MASSACHUSETTS.

STEAM GENERATOR.

1,413,863.

Specification of Letters Patent. Patented Apr. 25, 1922.

Application filed December 22, 1917. Serial No. 208,358.

To all whom it may concern:

Be it known that I, GEORGE B. MADDOCKS, a citizen of the United States, and a resident of Allston, county of Suffolk and State of

5 Massachusetts, whose post-office address is 41 Eastern Street, Allston, Massachusetts, have invented an Improvement in Steam Generators, of which the following description, in connection with the accompanying 10 drawings, is a specification, like characters on the drawings representing like parts.

This invention relates to steam generators. The objects and features of the invention will be best understood from the following 15 description, taken in connection with the accompanying drawings, of a steam generator embodying one form of my invention and selected for the purpose of illustration, it being understood that the invention in its 20 true scope is definitely set forth by the claims.

In the drawings:

Fig. 1 is a side elevation partly in section of a steam generator embodying one form 25 of my invention;

Fig. 2 is a sectional detail of one illustrative form of blow-off which may be used in said generator;

Fig. 3 is a top plan view showing a portion 30 of the economizer;

Fig. 4 is a sectional detail of one form of scale-catching attachment which may be used with said generator;

Fig. 5 is a top plan view of the banks of 35 generating tubes;

Fig. 6 is a sectional detail of one form of drum head;

Fig. 7 is a sectional detail of one form of junction box; and

40 Fig. 8 is a transverse section on line 8—8 of Fig. 1, and showing the tubes of the front bank and the junction box arrangement upon the left side of Fig. 1.

In the embodiment of the invention herein disclosed there are fourteen banks of generating tubes, only seven of which, however, are shown for the sake of simplicity, but it is to be understood that the number of banks of generating tubes may be varied according 45 to the size of the generator. These banks of generating tubes are disposed in parallel vertical planes, the upper tube 2 of each bank communicating with the water drum 4 by a tube 6, and the lower tube 8 of each bank communicating with the steam drum 5, by a tube 10. As all of said banks

of generating tubes are similar in construction and arrangement, a description of one of said banks will suffice for all.

Referring to Figs. 1 and 5, the tube 6 of the front bank of generating tubes leads vertically downward from the water drum 4 to a junction-box 12 with which communicates the right end of the upper generating tube 2 of said bank. The left end of this upper generating tube 2 communicates with a junction-box 14, with which also communicates the left end of another generating tube 16, the right end of which communicates with a junction-box 18. Another generating tube 20, Fig. 5, on the same level as the generating tube 16, communicates at its right end with the junction-box 18, and at its left end with a junction-box 22, Fig. 5, located behind the junction-box 14 and with which communicates the left end of another generating tube 23, Fig. 8, located below the generating tube 20 and in the same vertical plane as the latter, and communicating with its right end with a junction-box 24, Fig. 1. 80 With this junction-box 24 communicates the right end of a generating tube 26 located below and in the same vertical plane as the generating tube 16. The left end of the generating tube 26 communicates with a junction-box 28, with which communicates the left end of another generating tube 30 located below and in the same vertical plane as the generating tube 26, and having its right end communicating with a junction-box 32. With this junction-box 32 communicates the right end of another generating tube 31, Fig. 8, and having its left end communicating with a junction-box 34 located behind the junction-box 28, see Fig. 8, and 95 with which communicates the left end of another generating tube 36 located below and in the same vertical plane as the generating tube 31. The right end of this generating tube 36 communicates with a junction-box 38, with which also communicates the right end of a generating tube 40 located in the same vertical plane as the generating tube 30 and communicating at its left end with a junction-box 42. With this junction-box 42 100 communicates the left end of another generating tube 44, the right end of which communicates with a junction-box 46. With this junction-box 46 communicates the right end of another generating tube 48 located in the same vertical plane of the generating tube 36, and having its left end communi- 110

cating with a junction-box 50 located behind the junction-box 42, see Fig. 8. With this junction-box 50 communicates the left end of a generating tube 52, located in the same 5 vertical plane as the generating tube 48 and communicating at its right end with the junction-box 54. With this junction-box 54 communicates the right end of the lower tube 8 of said bank. This tube 8 is located 10 in the same vertical plane as the tube 44 and communicates at its left end with a junction-box 56 from which the tube 10 above referred to leads upwardly to a junction-box 58, Fig. 1, which communicates by a tube 60 15 with the steam drum 5 at the side of the latter.

As above stated, the other banks of junction-boxes are similar in construction and arrangement to that just described, the pipe 20 10 communicating with the steam drum 5 through a junction-box and pipe located in the same vertical plane as the junction-box 58 and pipe 60 of the first bank of generating tubes. In the same manner the pipes 6, leading 25 from the water drum to the first generating tube of each bank, are located in the same vertical plane.

It will be noted that by the arrangement 30 described of the junction-boxes for the generating tubes, said generating tubes are all disposed horizontally, with the exception of the lowest tube 8 of each bank, which are inclined upwardly toward their left ends, Fig. 1, thereby insuring that the tube 10 35 shall be free from water.

The economizer through which the water is fed into the water drum herein comprises 40 four horizontal banks of tubes 61, but it is to be understood that the number of said banks, and the number of tubes composing 45 the same, may be varied according to the size of the generator. The tubes of each bank communicate each with the next adjacent one, and the last tube of each bank with the first tube of the bank on the next level, by 50 means of junction-boxes 63, in such manner that the water, entering the economizer by the pipe 62 from a suitable source of supply, will circulate through the several banks of 55 tubes successively from the uppermost bank to the lowermost one and enter the water drum through the pipe 64 leading thereto from the lowermost bank. A pump of any usual and suitable construction, and driven 60 from any suitable source of power, may be used to pump the water from the source of supply, through the economizer into the water drum.

The junction-boxes will preferably all be 65 similar in construction. In the embodiment of the invention herein disclosed the tubes communicating therewith have their ends expanded and flared into said box. To this end, as shown in Fig. 7, circular openings 68 are provided in the wall of the junction-

box opposite that through which the tubes enter, said openings 68 having their inner edges bevelled and closed by plugs 70, having bevelled edged end portions 72, fitting the bevelled edges of said opening. Said 70 plugs are provided with shanks 74 extending through openings provided in yokes 76 projecting from the junction-box, the free ends of said shanks being screw-threaded to receive nuts 77 whereby said plugs may be 75 clamped securely in place.

It is to be noted that the steam and water drums and junction-boxes of the economizer tube and generating tubes are protected from the direct heat of the fire-box and setting, 80 said drums being, in the embodiment of the invention herein shown, located above the top firebrick wall 66 of the generator setting, and said junction-boxes outside of the vertical firebrick walls 78, 80, and 82 of the setting. This enables said drums and junction-boxes to be made of a thickness to withstand 85 very high pressure, the generator of my invention being intended to furnish a pressure of 800 pounds and over. To this end said 90 junction-boxes and drums will preferably be made of relatively thick steel castings. A thickness of $3\frac{1}{2}$ inches has been found adequate for the drum walls.

The invention also contemplates the provision of means to prevent the entrance of scale or other foreign matter with the water used in the generator, said means herein comprising a scale-catching attachment through which the water passes before entering the 100 tube 62 of the economizer. Said scale-catching attachment may be of any suitable construction, and in the embodiment thereof herein shown comprises a receptacle 84 closed at the top by a cover 86 bolted to a 105 flange 88 extending around the upper edge of said receptacle, by means of bolts 90. Said receptacle is provided with a central partition 92 extending downwardly approximately two-thirds of the depth of said receptacle, 110 the water from the supply entering said receptacle at one side of said partition through a pipe 94 and passing out of said receptacle through an opening provided in the wall of said receptacle, at the opposite side of said 115 partition from the tube 94, into which opening the end of the tube 62 is threaded or otherwise firmly secured. In this way, any scale or other foreign solid matter, entering said receptacle 84, will be arrested by the 120 partition 92 and, falling to the bottom of said receptacle, will settle there. A pipe 96 is herein shown as tapped into the bottom of said receptacle and provided with a valve 98 by opening which the scale that has collected from time to time may be removed.

My invention also contemplates a novel drum and drumhead construction, avoiding the use of rivets and seams, which are the weakest part of a drum, owing to their form- 130

ing a lodging place for scale, as will be readily understood by those skilled in the art, the drums being preferably cast in a single piece, for this purpose. In the embodiment of the 5 invention herein disclosed the drum heads 100, one of which is shown in detail in Fig. 6, are mounted to swing open and shut. To this end the drum head is provided with an ear 102 which is embraced between two ears 10 104, provided at the end of the drum proper, a pin 106 fitting through openings provided in said ears 102, 104 to act as a pivot. The end face of the drum is provided with an annular groove 108, within which fits an 15 annular tongue or rib 110 upon the inner face of the drum head, when said drum head is closed. To secure said drum head in closed position, any suitable means may be provided, said means herein consisting of bolts 20 112 extending through openings 114 suitably spaced around said head and registering with screw-threaded openings 116 provided in the end face of the drum and into which said bolts are screwed securely to fasten the 25 head in place.

Equalizing pipes are preferably provided connecting the two drums. Herein four such pipes are provided, communicating, on the one hand with openings suitably spaced 30 along one side of the steam drum 5, and, on the other hand with an equal number of openings suitably spaced along the top of the water drum 4. One of said pipes is shown at 118 in Fig. 1. Each of said pipes 35 will preferably be provided with a check-valve 120, opening toward the water drum. These check-valves may be of any suitable and usual construction and are too well-known to need further description. These 40 check-valves, as will be readily understood by those skilled in the art, will be preferably constructed and arranged to be normally closed and will of course remain closed while the boiler is in operation, but 45 may open when the boiler has no load.

A by-pass 122 will preferably be provided between the drum 4 and tube 62 of the economizer and a check-valve 124, opening downwardly, will preferably be provided in said 50 by-pass. This check-valve, like the others above referred to, may be of any suitable and usual construction and need not be herein more particularly described.

Preferably also, means will be provided 55 to drain off any water of condensation that may be formed in the steam drum, and to that end, in the above invention herein disclosed, two drainage pipes 125, 125 are provided, said drainage pipes communicating on 60 the one hand with openings suitably spaced in the bottom of the steam drum 5, and on the other hand with the junction-boxes, respectively, of the tubes 2 of two of the banks of generator tubes. Each drainage pipe 125

will preferably have a check-valve 127 opening downwardly. This may be of any usual and suitable construction and need not be more specifically described.

The invention further contemplates the provision of a separate blow-off for each 70 bank of generating tubes, said blow-off being located in the right-hand end, viewing Fig. 1, of the lowest tube 8 of each of the generating tube banks. Said blow-off may be of any suitable construction, and in the illustrative embodiment of the invention herein shown comprises a rotary valve 126, see Fig. 2, connected on the one hand by a pipe 128 with the base of the junction-box 54 into which the generating tube 8 opens, and on 80 the other hand by a pipe 130, with a main drain pipe 132 extending along the front of the generator on a level with the junction-boxes of the lower tubes 8 of all of the generating tube banks. All of the blow-offs 85 communicate with this waste pipe, thus affording convenient means for blowing off each bank of tubes separately, so as to be sure that each bank is clear.

My generator will also preferably be provided with a water gauge, said gauge being herein shown at 134 and being provided with suitable windows 136 of glass or other transparent material, through which the height of the water can be noted. The gauge communicates with the drum 4, by a pipe 138, and with the drum 5, by a pipe 140, the latter preferably containing a check-valve opening toward the gauge and away from the steam drum, to prevent water passing 100 over into the steam drum through the pipe 140, in case of a sudden demand for steam on the drum. This gauge also may be of any suitable and well-known construction and need not be described more fully herein. 105 A discharge-pipe 144, provided with a valve 146, communicates with the drum 4 and gauge 134.

The generator comprises the usual baffles 148, herein three such baffles being provided, but it will be apparent that the number of baffles used may vary with the number of tubes contained in the generator tube banks.

The drums 4 and 5 are supported by a 110 plurality of supporting yokes 150, only one of which for each drum is herein shown, said yokes being supported by supporting members 160 connected by U-beams 162.

Herein two grates 164 are provided which 120 are fed through doors 166. Several such doors 166 will be provided, as usual, upon either side. A plurality of doors 168 are also provided upon either side for withdrawing the ashes.

It is believed that the operation of my generator will be clear to those skilled in the art, from the description of the generator

above given, and that therefore no separate detailed description of the operation will be necessary.

It will be seen that the water, passing 5 downwardly by gravity from the water drum 4 through the banks of generator tubes, passes successively through zones of increasing heat from the less heated to the hottest, the water in this transition being 10 thus first converted into steam and the latter in passing through the hottest zone being superheated before ascending to the steam drum.

In accordance with my invention, the 15 water and steam are in separate drums, and the water in the water drum does not come in contact with the steam in the steam drum. As a result, the temperature of the steam in the steam drum is quite independent of and 20 unaffected by the temperature of the water in the water drum. It is thus unnecessary to heat the water drum and steam drum with the flue gases, the water being heated and steam being generated in the banks of generator tubes. The flue gases for these reasons can be, and in the generator of my invention are, sent out at a lower temperature than that of the steam, thus greatly economizing fuel. Furthermore, this enables both 25 drums to be located outside the firing zone or setting, and the steam drum can thus be made of metal of a thickness sufficient to withstand great pressure, 1,000 lbs. pressure, or even more being possible in a generator constructed in accordance with my invention. It is thus possible to develop an 30 enormous horsepower in a relatively small space and with great economy in fuel, etc.

In like manner the junction-boxes and 35 tube ends are protected from the action of the fire, being herein for that purpose located outside of the fire zone or setting, and so can be made of a thickness sufficient to withstand the highest pressure.

40 The separate blow-offs for each bank of generator tubes enable each bank to be blown separately, so that one can always be sure that each bank is clear.

45 By the provision of means to free the water entering the generator from scale, herein exemplified in the scale-catching attachment described, the entrance with the water of scale, or other solid matter, into the system is prevented.

50 Another advantage possessed by my invention resides in the provision of means, herein exemplified by the check-valves described, to prevent water from passing from the water drum through the equalizing tubes 55 into the steam drum, forcing the water into the generating tubes, thereby improving the circulation.

The drum head construction herein described also possesses advantages over those

heretofore used, that will be obvious to those 65 skilled in the art.

Other advantages resulting from my described invention, in addition to those pointed out above, will appear to those skilled in the art.

Obviously it is not indispensable that all 70 of the features of my invention be used conjointly, since they may be used to advantage separately in various combinations and sub-combinations. It will also be apparent that, 75 while the invention is herein described as embodied in the details illustrated, the invention is not to be considered as circumscribed by or limited to these details, or any one of them, but that said details may 80 be variously modified within the true scope of the invention, which is definitely set forth by the claims.

Having now described one specific embodiment of my invention, what I claim, and desire to secure by Letters Patent, is:—

1. In a steam generator, in combination, a water drum; a steam drum; one or more equalizing tubes connecting said drums; means to prevent the passage of water 90 through said equalizing tube or tubes from the water drum into the steam drum; an economizer for supplying said water drum with water; a setting; one or more banks of generator tubes, the tubes whereof extend 95 through said setting, the upper tube of said bank or banks of generator tubes being connected to the water drum, and the lower tube of said bank or banks of generator tubes being connected to the steam drum; 100 and junction-boxes for the tubes of said economizer and for the generator tubes, said junction-boxes and said water drum and steam drum being located outside the walls 105 of said setting.

2. In a steam generator, in combination, a water drum; a steam drum; one or more tubes connecting said drums; means to prevent communication through said tube or tubes from the water drum to the steam 110 drum, but permitting communication therethrough from the steam drum to the water drum; an economizer for supplying said water drum with water; a setting; one or 115 more banks of generator tubes, the tubes whereof extend through said setting, the upper tube of said bank or banks of generator tubes being connected to the water drum, and the lower tube of said bank or banks of generator tubes being connected to the steam drum; and junction-boxes for the tubes of said economizer and for the generator tubes, said junction-boxes and said water drum and steam drum being protected 120 from the fire in said setting.

125 In testimony whereof, I have signed my name to this specification.

GEORGE B. MADDOCKS.
